UNITED STATES PATENT OFFICE.

HAROLD R. BASFORD, OF SAN FRANCISCO, CALIFORNIA.

FOLDING CAMP-TABLE.

1,272,187.

Specification of Letters Patent. Patented July 9, 1918.

Application filed September 4, 1917. Serial No. 189,487.

To all whom it may concern:

Be it known that I, HAROLD R. BASFORD, citizen of the United States, residing at San Francisco, in the county of San Francisco, State of California, have invented a new and useful Folding Camp-Table, of which the following is a specification in such full and clear terms as will enable those skilled in the art to construct and use 10 the same.

This invention relates to a folding camp table, and its object is to produce a table which will fold into the least possible space for camping purposes and so forth.

15 An object of the invention is to provide for seats as well as for a place to set out food when the table is in use.

Another object of the invention is to produce a table which will be as light as it is 20 consistent with the necessary strength to support at least six people.

Other objects of the invention will appear as the description proceeds.

An embodiment of the invention is shown 25 in the drawings in which the same reference numeral is applied to the same portion throughout, but I am aware that there may be modifications thereof.

Figure 1 is an end elevation of the table 30 showing the way it appears when set up,

Fig. 2 is a side elevation of the table shown in Fig. 1,

Fig. 3 is a plan view of one half of the table frame when folded down, and

35 Fig. 4 is a back view and elevation of one of the long hooks for the two sections forming the table.

Fig. 5 is a detail view showing the manner of operation of the top rails of the 40 table.

The table has four legs 1 to 4 inclusive. The legs are respectively pivotally connected near their centers to cross angle iron bars 5, 10 and 5', 10'. The bar 5 is connected by 45 means of a hinge 6 to a similar angle bar 10, and maintained in the extended position by means of a heavy spring 8 on the end of the bar 5, and which is adapted to engage a pin 9 on the bar 10 when said bars 50 are extended. The position of the leg with respect to the cross bar 5 is determined by means of the brace 11 which is pivotally

connected with the bar 2 and has a pin 12 adapted to pass through the hole 13 in the bar 5.

55 A similar construction is used at the opposite end of the bar 10 where the brace 14 is pivotally connected with the leg 1, and has a pin 15 which engages a slot 16 in the bar 10. Boards 17 and 18 are placed upon 60 the cross pieces 5, 5' and 10, 10' for seats, two of the frames just described being connected together to form the complete table frame.

The legs 1, 2, 3 and 4 respectively each 65 have an angle bar pivotally connected to them at their upper ends as indicated at 19, 20, 21 and 22, and they are held in a horizontal position by means of the braces 23, 24, 25 and 26, while they are connected together by means of the two projecting plates 27, 28, the former plate having a long horizontally extending slot 29 to receive a pin 30, while the plate 28 has a vertically 70 extending slot 31 to receive a pin 32 extending in back of the angle bar 19. The two sections of which the table is made, after 75 being set up in the form illustrated in Fig. 1, and after having the braces connected thereto, are connected to the frame at the 80 opposite end of the table and disconnected therefrom in the manner illustrated in Fig. 5, simply lifting up upon the horizontal members serving to disconnect them when connected and pushing down upon them 85 serving to connect them when that is necessary.

A table top consisting of a series of boards 34 all connected together by means of the two tapes 35, 36, serves to place objects upon 90 the table in front of the persons seated on the boards 17 and 18.

Having thus described my invention what I claim as new and desire to secure by Letters Patent of the United States, is as follows, express reservation being made of 95 permissible modifications.

1. A camp table comprising four transversely extending members hinged together in pairs and adapted to provide a support 100 for two seats, four legs pivotally connected with said transversely extending members, four longitudinally extending members adapted to be detachably connected to

gether in pairs at their ends to support a table top, and suitable braces for holding the entire frame rigid.

2. A camp table comprising two pairs of legs, two members pivoted to each pair of legs and to each other, two other members pivoted to the cross pairs of legs, means to detachably connect the latter members whereby a rigid table frame is produced,

projections on certain of the members piv- 10
oted to the legs for a seat support, braces from the seat support to the legs, and a spring catch for locking the seat support in a horizontal position.

In testimony whereof I have hereunto set 15
my hand this 24th day of August A. D. 1917.

HAROLD R. BASFORD.
